UNITED STATES PATENT OFFICE.

GEORGE E. SAVAGE, OF MERIDEN, CONNECTICUT.

DESIGN FOR A CHAFING-DISH COVER.

No. 38,812.

Specification for Design.

Patented Sept. 17, 1907.

Application filed August 13, 1907. Serial No. 388,422. Term of patent 7 years.

To all whom it may concern:

Be it known that GEORGE E. SAVAGE, a citizen of the United States, residing at Meriden, county of New Haven, State of Connecticut, has invented a new, original, and ornamental Design for a Chafing-Dish Cover, of which the following is a full, clear, and exact description.

My invention relates to a new, original and ornamental design for a chafing dish cover.

In the accompanying drawings, Figure 1 is a plan view, and Fig. 2 is a side elevation of the same.

The salient features of this design are the flat panels alternating with the combined concaved, convexed, concaved flutings as shown.

I claim:—

The ornamental design for a chafing dish cover as shown.

GEORGE E. SAVAGE.
